CLARENCE W. LANNOM, OF OAKLAND, CALIFORNIA.

WALL-TABLE CABINET.

Application filed November 3, 1924. Serial No. 747,403.

This invention relates to wall-table cabinets, and especially to cabinets for installation in apartments, flats and rooms wherein floor space is limited and consequently must be used to the greatest and maximum advantage.

An important object of my invention is the provision of a cabinet having a folding panel formed as a part thereof which may be lowered to form the table for the room, and when not in use may be swung to an upright position and out of way, thus permitting the floor area just occupied by the table to be used again for other serviceable purposes.

Another object is the manufacture of the cabinet as a piece of furniture for recessing in, or to be built in the walls of the structure to conserve additional floor space.

Another object is the provision of unique and novel means for supporting the table member in the cabinet and the manner of lowering it to a position extremely rigid.

Another object is the provision of means for concealing the working parts of the table from view and interference, making available uninterrupted maximum storage space in the cabinet.

Another object is to support the panel in its normal vertical position by pins fixed in the cabinet, and to support the panel in its lowered position by side bars pivoted on the pins and having extensions abutting a rigid stop.

A further object is to form grooves in the sides of the cabinet of predetermined shape, and to provide the table member with means to engage the grooves, such, that in the lowering of the table to position the grooves will cause the table to be pushed outward to make the full area of table available for use.

And a still further object is the provision in a cabinet of the above type, of a table having no legs nor braces thereunder of any kind, thereby eliminating foot, knee and broom obstruction.

In addition to the above broader features of the invention, there are certain details of design, whereby compactness, durability of structure, and positiveness and ease of operation are attained, and which details are shown on the accompanying two sheets of drawings illustrating the present embodiment of my invention, and what I claim as new, is particularly pointed out in the appended claims following this specification.

In the drawings: Figure 1 is a front view of the cabinet as it appears when closed.

Fig. 2 is a vertical cross-section of the cabinet taken on the line 2-2 of Fig. 1 and drawn to a larger scale. The panel is shown swung to the table position. The dot-and-dash lines represent the panel in an angular descending position.

Fig. 3 is a horizontal cross-section of Fig. 2 along the line 3-3 thereof; and Fig. 4 is a similar section thereat but enlarged for clarity.

Fig. 5 is a side view of the table unit of Fig. 4. The dot-and-dash figure is the pin plate of the invention.

Fig. 6 is a fragmentary front view of Fig. 4 along the line 6-6 thereof; the scale is greatly enlarged.

Fig. 7 is a fragmentary front view, on an enlarged scale, of the corner of the cabinet directly thereabove, the door thereat being removed to show clearly the position of the side bar extension, the panel being in closed position.

Fig. 8 is a perspective view, on a reduced scale, of the open cabinet as it appears partially recessed or built in a wall.

Adverting to the drawings and figures thereof: The numeral 9 represents the cabinet in general and as having any desired number of shelves 10 therein, and conventional upper and lower compartments 11 and 12; and which compartments may have hinged doors 13 and 14 forming part of the front of the cabinet. The balance of the front consists of a suitably shaped panel 16, pivotally supported in the cabinet by pins 17 projecting from a plate 18 recessed and secured to the cabinet sides 19 as by screws 20. Fig. 6.

To each side edge of the panel is recessed and secured a metallic bar 21, having one end 22 extended a distance substantially equal to that of the depth of the cabinet for supporting purposes as will be described. A portion of each bar near the extension 22 is slotted or grooved as at 23 to receive the pin 17, the groove being of sufficient length to accommodate the sliding movement of the panel over the pin in the lowering of the panel to form the table. At the extremity of each extension a roller 24 is attached, Fig. 4, serving as a projection and guide to ride in a groove 25 preferably parabolic in shape, Fig. 2, formed in each side 19 of the cabinet.

A shelf 26 usable also for a stop or abutment is secured in the cabinet adjacent the pins 17, in a position that will determine the horizontal and limiting position of the panel 16.

Partition boards 27 are secured in the cabinet between the shelf 26 and the bottom of the cabinet spaced from the sides 19 to freely incase the extensions 22, thereby permitting a maximum amount of space to be utilized as storage without danger of the moving extensions catching or interfering with the stored or deposited goods in any way; also the working parts will be obscured from view. Part of the partition boards is cut away as at 28, Fig. 2, to allow for clearance of the end 29 of the panel in its movement from one position to the other.

The panel in its vertical or closed position rests on the lower shelf 30 and also abuts and conceals the shelves.

When it is desired to utilize the cabinet as a table, the handle 31 is pulled and the panel 16 moves outwardly and downwardly, slowly and firmly, guided at one extremity by the rollers 24 riding in the parabolic grooves 25, and the panel side bars 21 sliding and pivoting on the pins 17 until the at-rest or table position of the panel is reached, by reason of the extensions 22 abutting the under-surface of the stop-shelf 26. The table in this position is most rigid and stable and without any lateral play. It will be observed that the table is entirely free of legs and angular braces of any sort for supporting the table outside of the cabinet, and this accomplishment permits a much desired freedom of the feet thereunder. Also it will be observed that the full surface of the table is usable although the pivot point of the panel when closed assumes a position well above the end of the panel. The long parabolic groove enables one to easily reach the end of the panel and permits the movement of the same to be easily controlled.

The fact should not be overlooked that, in swinging the panel to a vertical or to a horizontal position, a person is rendered a most valuable aid by means of the parabolic grooves 25, which during the panel's swinging movement automatically guide the rollers 24 in a manner especially intended to minimize his labor and to economize his strength. Probably this is best understood by reference to Figure 2, in which one groove 25 is indicated by two dotted lines representing respectively the outer and the inner periphery of the groove. For the purpose of further explanation I shall refer to the outer periphery as the outer side wall, and to the inner periphery as the inner side wall of the groove. The dotted lines in Figure 2 illustrate clearly how the curvature of each groove 25 is gradually increased from the upper end of the groove until it is greatest

at the lower end thereof, this curvature being in accordance with the accepted shape of a parabola.

From the foregoing observations it is evident that, when the rollers 24 are ascending in the grooves 25, that is, when the panel 16 is swung towards the horizontal position, the tendency during the entire length of the ascending movement of the rollers is for each roller to press against the outer side wall of its respective groove, and the pressure against the outer side walls increases in proportion as the panel approaches its horizontal position, and in proportion as the weight of the panel may have a tendency to increase the speed of the panel's swinging movement towards the horizontal position. It is therefore evident that very little effort is required to initiate the panel's swinging movement from the vertical to the horizontal position, and, as the panel is swung still farther from the vertical position, the weight of the panel assists the swinging movement, while at the same time, being automatically guided in their continuously curved paths from a nearly horizontal initial movement to a movement that is gradually approaching one nearly vertical towards the termination of the path, the rollers cause an easy forward, sliding movement of the panel until it has assumed the horizontal position. It is thus seen that the parabolically curved paths of the rollers are an aid to a moderately speedy movement of the panel to its horizontal position, but, if for any reason a force should be applied that has a tendency to increase the speed of the swinging movement beyond the moderate limit, such as, for instance, by a person's accidentally losing control of the panel and permitting it to swing outwardly and downwardly by its own weight, the rollers 24 will bear with correspondingly increased pressure against the outer side walls of the respective grooves and thereby prevent a too hasty descent of the panel to the horizontal position and thus safeguard the wall-table cabinet from damage.

Conversely, it should be observed that, when an initial swinging movement is made of the panel from its horizontal towards its vertical position, the initial movement of the rollers 24 in their respective grooves is nearly vertical, or downward and slightly forward, the rollers then having a tendency to press against the inner side walls of the grooves, thus aiding the inward sliding movement of the panel until a point is reached when the weight of the panel will cause the rollers again to bear against the outer side walls of the grooves, in the curved paths of which in the meantime the rollers are automatically guided from the nearly vertical movement to a movement that is gradually approaching one nearly horizontal

tal towards the lower ends of the paths, so as to assure an easy, forward sliding movement of the panel at a moderate speed until the panel has assumed its vertical position in the cabinet.

I am aware that in the previous art means have been provided for guiding the inner end of a swinging board in a straight path extending obliquely upward. In order to accomplish the board end's travel in such a path without binding it was found necessary to provide auxiliary members, pivotally secured to the board and also to a support therefor. Without such double pivoting means the device would bind and be inoperative even if the path of travel for the end of the board had been changed from a straight to a curved one.

It has also been shown in the previous art that a swinging member has been provided with slots in each of its side walls and that a rod has been extended through the slots from a support on each side of the member for pivotally securing the member to the supports. By this means the end of the member has been caused to travel in a circular path, but no suggestion has been made of means that would pull the member forwardly or push it inwardly simultaneously with the swinging of the member to the respective horizontal or vertical position, as the case may be, and also would be automatically operated by the swinging of the member. In such a swinging member the pushing or pulling is accomplished only by manual operation. Moreover, the pivotal rod also has been found to be an obstruction, as it would not permit the storing of goods back of the swinging member, when the member has been swung to the vertical position.

It is thus clear that my invention of table cabinets having the pivotal means for the panel arranged on a single axis, and the means for guiding the end of the panel in a path so as to produce automatically a forward and inward sliding movement of the panel by the swinging of the panel and simultaneously with the panel's swinging

movement, is distinctly novel and has great advantages over the prior art. 50

What is claimed is:

1. A wall-table cabinet comprising a structure of shelving and a front panel adapted to fold and conceal the shelving when in closed position; each side of the cabinet provided with a fixed pivot pin, said pins being in axial alignment and each side edge of the panel provided with a member attached thereto and extending beyond one end thereof, grooves formed in the unextended portion of the member for the reception of the pins, the latter pivotally and slidably supporting the panel, one of said shelves secured in the cabinet adjacent said pins for the abutment to the underside thereof of the said extensions to determine the horizontal position of the panel, the said positioned panel forming the table of the structure; and the end of each extension provided with a roller adapted to roll in a groove formed in each side of the cabinet to guide the panel automatically in its sliding movement; and partition boards secured in the cabinet near the said sides to incase the said extensions and rollers to prevent interference from goods that may be stored in the cabinet space between said partition boards. 65

2. In a wall table cabinet having a front opening, a fixed pivot pin at each side of said opening and located above and in vertical alignment with the bottom edge of said opening, a panel member for said opening, extensions upon the sides of said panel member extending into said cabinet and having grooves therein in which said pivot pins are adapted to slide, projections upon the ends of said extensions and tracks within said cabinet with which said projections cooperate to lower the bottom edge of said panel member to the bottom of said opening when raised to vertical position and to extend said panel member away from said cabinet when lowered to horizontal position. 80 85

In testimony whereof I affix my signature.

CLARENCE W. LANNOM.
